UNITED STATES PATENT OFFICE

2,598,614

BELT HANGER

Hilda Gilbert, Cleveland, Ohio

Application March 2, 1950, Serial No. 147,240

2 Claims. (Cl. 211—113)

1

This invention relates to belt hangers for holding a plurality of belts.

One of the objects of the invention is to provide a belt hanger for holding a plurality of belts wherein each independent belt engages an independent holding edge of the hanger.

Another object of the invention is to provide a transparent belt hanger wherein both the belt and the buckle may be seen from either side of the hanger.

Another object of my invention is to provide an economical belt hanger for holding a plurality of belts in an orderly manner.

Other objects and a fuller understanding of this invention may be had by referring to the following description and claims, taken in conjunction with the accompanying drawing in which:

Figure 1 is a front elevational view of the belt hanger;

Figure 2 is a fragmentary sectional view along the line 2—2 of Figure 1; and

Figure 3 is a fragmentary sectional view along the line 3—3 of Figure 1.

The belt hanger illustrated and described herein is designed for holding a plurality of belts, some of which have buckles thereon and some of which do not have buckles thereon. For purposes of description, the belt is generally referred to as a flexible strap provided with a buckle on one end thereof.

The belt hanger illustrated in Figure 1 is provided with a plurality of horizontal transparent bars, such as the bar 10. Although the drawing illustrates a specific number of horizontal transparent bars, it is understood that any number of these bars may be used and that the bars are spaced apart vertically. In this instance, the bars are supported at the ends thereof by framework having end members 11 and a top cross-member 12. A hook 13 may be fastened to the center of this top cross-member 12 so that the entire belt hanger may be easily hooked over a clothes closet rod or other similar member.

Each horizontal transparent bar 10 is provided with opposite vertical surfaces 15 and 16 respectively, as best illustrated in Figure 2. These surfaces 15 and 16 are spaced apart a distance equal to the horizontal thickness of the bar. The surfaces 15 and 16 have a length equal to the length of the horizontal transparent bar and thus also equal to the distance between the end members 11. The vertical surfaces 15 further have a vertical height equal to the vertical height of each horizontal transparent bar. Each bar 10 is pro-

2

vided with a plurality of elongated slots 17 defined by slot surfaces 18 and 19. As is best illustrated in Figure 2, these slot surfaces 18 and 19 are spaced apart a distance greater than the thickness of a belt which is to be inserted therebetween. The slot surfaces extend generally longitudinally of the bar and meet the vertical surfaces of the bar at angles other than right angles. Since the slot surfaces 18 and 19 are at an angle other than right angles to the vertical surfaces of the bar, edges 20 and 21 are formed. The edge 20 is at one surface and the edge 21 is at the opposite vertical surface of the bar.

In the drawings and especially in Figure 2, a belt is illustrated as having flexible strap 22 and buckle 23. In hanging the belt, the flexible strap 22 engages at least one of the edges 20 or 21 and the buckle 23 engages one of the vertical surfaces 15 or 16. In Figure 2, the flexible strap 22 engages the edge 21 with the strap hanging down from the vertical surface 15 and the buckle abutting the other vertical surface 16 of the horizontal transparent bar 10. Since the horizontal bar 10 is transparent, both the belt and the flexible strap are easily visible for quick identification.

In Figure 1 and in Figure 3 of the drawings, some of the horizontal bars are illustrated in the form of rods 25. These rods 25 are horizontally positioned and spaced apart in the same manner as the other bars such as the horizontal transparent bars 10. A plurality of spring operated clips 26 are slidably mounted on each of these rods 25. Each of these clips 26 is provided with a spring 27. The clips 26 will receive and hold any belts not provided with buckles or any other small clothing article such, for example, as gloves.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A belt hanger for supporting a plurality of belts, comprising two spaced vertical frame members, a plurality of vertically spaced flat bars connected to said frame members, said bars having a small thickness dimension relative to said width dimension, the width dimension extending vertically, surfaces on said bars defining elongated horizontal slots through the thickness of said bars adapted to receive one belt strap in each of

said slots with the belt buckle abutting one vertical face of said bars, each of said bars being made of a relatively hard non-pliable transparent material to permit viewing both the belt strap and the belt buckle from either side of the belt hanger, the slots of different bars being other than in vertical alignment to thus facilitate viewing an assortment of belts threaded through the various slots, at least the lower surface defining each of said slots being disposed at an acute angle to the horizontal to establish a sharp knife edge surface upon which a belt strap will lie when threaded through one of said slots, thereby providing a firm gripping action with the belt strap to prevent the belt strap from sliding through the slot despite the weight of a buckle on the belt strap.

2. A belt hanger for supporting a plurality of belts, comprising two spaced vertical frame members, a horizontal cross member joining said frame members at the ends of the cross member, a hook on the cross member for attaching the belt hanger to any suitable support, a plurality of vertically spaced flat bars connected to said frame members, said bars having a small thickness dimension relative to said width dimension, the width dimension extending vertically, surfaces on said bars defining elongated horizontal slots through the thickness of said bars adapted to receive one belt strap in each of said slots with the belt buckle abutting one vertical face of said bars, each of said bars being made of a rela-

tively hard non-pliable transparent material to permit viewing both the belt strap and the belt buckle from either side of the belt hanger, the slots of different bars having different lengths and the slots in a given bar having substantially equal lengths so that the slots are randomly placed and not in vertical alignment to thus facilitate viewing an assortment of belts threaded through the various slots, said surfaces defining each of said slots being disposed at an acute angle to the horizontal to establish a sharp knife edge surface upon which a belt strap will lie when threaded through one of said slots, thereby providing a firm gripping action with the belt strap to prevent the belt strap from sliding through the slot despite the weight of a buckle on the belt strap.
